UNITED STATES PATENT OFFICE

96,024

DESIGN FOR A SHOE

Vincent De Liso, Astoria, N. Y.

Application February 27, 1935, Serial No. 55,642

Term of patent 3½ years

To all whom it may concern:

Be it known that I, Vincent De Liso, a citizen of the United States, residing in Astoria, Long Island, New York, have invented a new, original, and ornamental Design for a Shoe, of which the following is a specification, reference being had to the accompanying drawing, forming part thereof.

Figure 1 is a plan view of a shoe showing my new design.

Figure 2 is a side perspective view of the shoe.
The dominant feature of the present design

resides in the combination of ornamental features obtained by the overlapping of the elements which make up the vamp and upper quarters and which provide several small openings near the ankle strap in the upper quarter and which also provides several small openings near the side of the T-strap.

I claim:

The ornamental design for a shoe, as shown and described.

VINCENT DE LISO.
